ATTORNEY.

UNITED STATES PATENT OFFICE.

JAMES POTT, JR., OF NEW YORK, AND EDWIN S. GORHAM, OF BROOKLYN, N. Y.

BOOK HOLDER AND CARRIER.

SPECIFICATION forming part of Letters Patent No. 313,021, dated February 24, 1885.

Application filed December 16, 1884. (No model.)

To all whom it may concern:

Be it known that we, JAMES POTT, Jr., of the city, county, and State of New York, and EDWIN S. GORHAM, of Brooklyn, county of Kings, and State of New York, citizens of the United States, have invented certain new and useful Improvements in Book-Holders, of which the following is a specification, reference being had therein to the accompanying drawings.

Our invention relates to devices for holding books—such as hymn and prayer books; and it consists in the novel features of construction hereinafter described, whereby an article of superior utility is obtained.

In the accompanying drawings, Figure 1 is a cross-section of a holder containing our invention. Fig. 2 is a like section, showing the holder in position for use. Fig. 3 is a like section of a book used in connection with the holder. Fig. 4 is a side view of the holder in position similar to that shown in Fig. 2.

Similar letters indicate similar parts. The letters A, B designate two books, one 25 of which is provided with a pocket, C, on the exterior, opening in the direction of the back thereof, for the reception of one side of the cover of the other book.

The letter D indicates a strap forming the holder proper, the strap being adapted to envelop both of the books A, B, as indicated in Fig. 2, and being provided with a clasp or lock, E, for retaining it in position.

To that portion of the strap D which is 35 brought opposite to the free edges of the books

A B when in use is connected a second strap, F, constituting a handle, the ends of this strap being inserted in bridges to slide toward and from the main or holder strap in a well-known manner.

At a point intermediate of the ends of the holder-strap D the latter is provided with a leaf, G, which is adapted to enter the pocket C of the proper book, so that when the holder is put in place this leaf tends to steady or prevent it from shifting, thereby keeping the handle-strap in symmetrical and proper position for carrying the books.

It will be seen that by this construction a very simple, cheap, and convenient holder is obtained.

We do not claim in this application a construction of books herein shown and described, but reserve the right to make such the subject-matter of a separate application for Letters Patent.

What we claim as new, and desire to secure by Letters Patent, is—

A book-holder consisting of the strap D, having the handle F and the steady-leaf G, substantially as and for the purposes described.

In testimony whereof we affix our signatures in presence of two witnesses.

JAMES POTT, JR.
EDWIN S. GORHAM.
